HEATER FOR THERMALLY EXPANDING BEARINGS FOR MOUNTING PURPOSES OR THE LIKE

Clyde C. Cone, 7395 W. 67th Ave.,
Arvada, Colo. 80002

Filed May 8, 1968, Ser. No. 11,851

Term of patent 14 years

Int. Cl. D23—03

U.S. Cl. D23—77

FIG. 1

FIG. 1 is a top plan view of a device for heater for thermally expanding bearings for mounting purposes or the like, showing my new design; and

FIG. 2 is a side elevational view thereof.

I claim:

The ornamental design for a heater for thermally expanding bearings for mounting purposes or the like, as shown.
